OF 12,898

DESIGN FOR A HEATING-STOVE.

Design No. 12,898, dated April 18, 1882.

UNITED STATES PATENT OFFICE.

JOHN W. KENNEDY, OF TROY, ASSIGNOR TO THE UNION STOVE WORKS,
OF NEW YORK, N. Y.

DESIGN FOR A HEATING-STOVE.

SPECIFICATION forming part of Design No. 12,898, dated April 18, 1882.

Application filed March 15, 1882. Term of patent 7 years.

To all whom it may concern:

Be it known that I, JOHN W. KENNEDY, of the city of Troy, county of Rensselaer, and State of New York, have invented a new and original Design for the Ornamentation of Heating-Stoves, of which the following is a specification.

My invention relates to the ornamental form and surface ornamentation of a heating-stove and its parts, as illustrated in the annexed photograph, forming a part of this specification.

My invention of a design consists, first, in the ornamental horseshoe form A, as applied to the stove-top, it having the ornamentation a' upon its upper and toe end, with its heel-prongs curved upwardly within the shoe to receive a trefoil figure, a^2 , the shoe having the word "Luck" displayed on its face, and being connected by the curved studs b with the cuniform base B, and the latter having in revolution upon its exterior the moldings b^2 b^3 b^4 .

Second, my invention also consists in the form and ornamentation of the top cover of the stove, (designated at C,) and composed of the rectangular top flat panel, c' , bordering-fillet c^2 , oval molding c^3 , base-fillet (below the latter) c^4 , and the subtending top proper, having the top flat surface, c^5 , and the exterior beveled edge, c^6 .

Third, my invention also consists in the form and surface ornamentation of the end extensions of the stove, (designated at D D,) and composed of the exterior vertical recessed panel, d' , having the doubly-filleted border d^2 and the central relief ornamentation, d^3 , the sides of the extension D and the top of the latter, where they unite at the front with the vertical face, having the moldings d^4 d^5 , and the extension D, having the rounded corners d^6 d^7 at the top, the projecting and molded base d^8 , and the fluted ornamentation d^9 where uniting with the stove-body.

Fourth, my invention also consists in the manner of ornamenting the panels E E, formed upon each of the upper doors in the stove-front, the panels being recessed and bordered by a beaded molding with radiate fan ornaments in the corners, and the center of the panels ornamented with two reversing horseshoe fig-

ures in relief, with the prongs of the shoes continued, so as to interlace and loop within the shoes, as designated at e' e^2 .

Fifth, my invention also consists in the ornamentation of the lower doors, F F, and the display on their exterior surfaces of the molded and bordered panels f' f^2 , and the horseshoe figure f^3 , the latter being in relief and having the shoe-prongs continued up within the shoe to receive a trefoil figure.

Sixth, my invention also consists in the design for the ornamentation of the feet of the stove, produced by means of a horseshoe figure in relief on a bordered panel on the front of the foot, as shown and designated at O.

Having thus described my invention of an ornamental design for the parts of a heating-stove, what I claim, and desire to secure by Letters Patent, is—

1. The ornamental design for the stove-top, consisting of the horseshoe form A, having the top ornamentation, a' , and the interior ornamentation, a^2 , arranged upon the prongs of the shoe, as shown and described.

2. The ornamental design of the stove-top and its support, in combination, consisting of the horseshoe form A, curved studs b b , the cuniform base of the top B, and the moldings b^2 b^3 b^4 in revolution upon the latter, as shown and described.

3. The design for the ornamentation of the top cover of the stove and as designated at C, consisting of the rectangular flat top panel, c' , bordering-fillet c^2 , oval moldings c^3 , base-fillet c^4 , and the subtending top proper, having the projecting top surface, c^5 , and the exterior beveled edge, c^6 , as shown and described.

4. The design for the ornamental form and surface ornamentation of the end extensions of the stove-body, (designated at D,) and in combination, consisting of the vertical panel d' , having the doubly-filleted border d^2 , the central relief ornament, d^3 , the moldings d^4 and d^5 , where the sides and outer ends of the extensions unite, the rounded top corners, d^6 d^7 , the projected and molded base d^8 , and the fluted ornamentation d^9 , applied to the sides of the extensions where the latter attach to the stove-body, as shown and described.

5. The design for the ornamentation of the panels E E upon the front of the stove at the sides of the doors, and consisting of the beaded borders, fan ornaments in the corners, and the 5 double reversing horseshoe figures e' e', and their ornamentation as arranged in the center of the panel, as shown and described.

6. The design for the ornamentation of the doors F F, consisting of the molded and bordered panels f' and the horseshoe figures f² in relief on the panels, as shown and described.

7. The design for the ornamentation of the exterior surface of the feet, consisting of the panel O and the relief figure of a horseshoe 15 played in the panel, as shown and described.

8. The design for the ornamentation of a

stove, in combination, consisting of the form and ornamentation of the horseshoe top A, base of the top B, the studs b b, which connect the latter with the former, the form and ornamentation of the top proper, (designated at C,) end extensions, D D, and their ornamentation, panels E E, doors F F and their ornamentation, and the ornamentation of the feet O, as shown and described.

Signed at Troy, New York, this 30th day of December, 1881.

JOHN W. KENNEDY.
